(57) **CLAIM**

The ornamental design for a tip for a ground engaging machine implement, as shown and described.

DESCRIPTION

FIG. 1 is an upper, right-side perspective view of a tip for a ground engaging machine implement showing my new design;

FIG. 2 is a front view thereof;

FIG. 3 is a rear view thereof;

FIG. 4 is a right side view thereof, the left side view being a mirror image thereof;

FIG. 5 is a top view thereof;

FIG. 6 is a bottom view thereof; and,

FIG. 7 is a bottom, right side perspective view thereof.

The relatively light and dark shade lines indicate contour and not surface decoration.

The dashed broken lines are for the purpose of illustrating portions of the tip of a ground engaging machine implement and form no part of the claimed design.

The dot-dash broken lines represent unclaimed boundaries and form no part of the claimed design.
